HAND LOOM

John P. Bexell, Pontiac, Mich.

Application June 11, 1941, Serial No. 397,601

1 Claim. (Cl. 139—33)

This invention relates to hand looms.

An object of this invention is to provide a hand operated loom which is simple in construction and may be used with various types of yarns.

Another object of this invention is to provide a loom of this character having an improved beater for beating or packing the weft, the beater being swingably supported by an improved mechanism, which will permit the shifting of the fulcrum and raising or lowering of the beater to thereby position the beater in the desired position for convenient operation.

A further object of this invention is to provide a loom of this kind in which springs have been omitted for operation of the heddle harnesses, the harnesses being shifted in one direction by counterbalancing lams, and shifted in the other direction by foot operated pedals or levers.

A further object of this invention is to provide a frame structure formed entirely out of wood having portions thereof connected together by mortise and tenon joints which are glued together, and having other portions thereof connected together by wedge-locked tongues so that the frame will not become loosened under vibrations.

A further object of this invention is to provide improved winding drums for the warp and the woven cloth, which will provide an even tension on the warp.

To the foregoing objects and to others which may hereinafter appear, the invention consists of the novel construction, combination and arrangement of parts as will be more specifically referred to and illustrated in the accompanying drawings, wherein is shown an embodiment of the invention, but it is to be understood that changes, variations and modifications may be resorted to which fall within the scope of the invention as claimed.

In the drawings:

Figure 1 is a detail front elevation of a hand operated loom constructed according to an embodiment of this invention.

Figure 2 is a detail rear elevation of the loom.

Figure 3 is a detail side elevation partly broken away and in section of the loom.

Figure 4 is a sectional view taken on the line 4—4 of Figure 1.

Figure 5 is a fragmentary side elevation partly broken away and in section of the cloth drum support, and

Figure 6 is a sectional view taken on the line 6—6 of Figure 3.

Referring to the drawings the numeral 10

designates generally a frame structure which includes vertically disposed side members generally designated as 11 and 12, which are connected together by a plurality of horizontally disposed transverse connecting members to be hereinafter described. The two side members 11 and 12 are of identical construction and the description of one of these side members, such as the side member 11, will apply equally as well to the description of the side frame member 12.

The side frame member 11 includes a vertically disposed front post 13 and a rear vertically disposed post or frame member 14, which is substantially longer than the front frame member 13. A horizontally disposed connecting bar 15 connects the lower end portions of the frame members 13 and 14 together, the opposite ends of the connecting bar 15 being provided with tenons 16, which are adapted to be adhesively secured in mortises 17 which are formed in the vertical frame members 13 and 14 at a point slightly upward from the lower ends of the frame members 13 and 14. An upper horizontally disposed and forwardly extending bar 18, which is formed at its rear end with a tenon 19 engaging in a mortise 20 formed in the upper portion of the forward side of the rear member 14 is braced in a horizontal position by means of a vertically disposed bracing member 21. The bracing member 21 is formed with a tenon 22 engaging in a mortise 23 formed in the lower side of the upper supporting bar 18 at a point intermediate the ends of the bar 18.

The lower end of the bracing bar 21 is also formed with a similar tenon engaging in a mortise formed in the upper side of the lower connecting bar 15. The side member 11 also includes a horizontally disposed forward bar 24, which is formed at the opposite ends thereof with tenons 25 and 26 engaging in mortises 27 and 28 formed in the rear side of the vertical frame member 13 and the forward side of the connecting or bracing member 21 respectively. A vertically disposed bearing supporting member 29 is formed at the opposite ends thereof with tenons 30 engaging in mortises 31 formed respectively in the connecting member 24 and the upper side of the connecting member 15. The bearing member or support 29 is disposed substantially midway between the front frame member 13 and the vertical connecting member 21.

The two side frame members 11 and 12 are connected together at their forward portions by means of a lower forward connecting bar 32, which is formed at the opposite ends thereof with

reduced tongues 33 and 34 extending through openings 35 and 36 respectively formed in the lower end portions of the front frame members 13. The tongues 33 and 34 are each formed with openings or slots 37 and 38 respectively in which wedges 39 and 40 are adapted to engage. The wedges 39 and 40 engage on the outer sides of the frame members 13 so as to tightly hold these frame members relative to the horizontal front connecting bar 32. A rear lower connecting bar 41 is formed at the opposite ends thereof with reduced tongues or extensions 42 and 43 engageable through openings provided in the rear frame members 14 and wedges 44 and 45 engage through the tongue openings and against the outer sides of the frame members 14, so as to tightly hold the rear vertical frame members 14 relative to the horizontal rear frame member 41.

An upper connecting frame bar 46 is provided at the opposite ends thereof with reduced tongues 47 and wedges 48 engage through slots or elongated openings 49 formed in the tongues 47, so as to tightly hold the upper horizontal frame members 18 together. An intermediate connecting bar 50 formed at the opposite ends thereof with reduced tongues 51 engaging through openings 52 formed in the vertical connecting members 21 is tightly held between the vertical frame members 21 by means of wedges 53. By connecting the side frame members 11 and 12 together through the medium of the horizontally disposed connecting bars which are held in position by wedges, the side frame members 11 and 12 are thus detachably connected together and by forming each side member as a unit with the several parts forming each side member glued together the frame structure will not become loosened under normal vibrations in the use and operation of the loom and the loom may be taken apart and reassembled without the use of tools other than a hammer or the like.

A breast roll 54 is rotatably disposed between the upper end portions of the front frame members 13 being mounted on pivot members 55, which engage through the frame members 13. A cloth winding roll or drum generally designated as 56 is rotatably disposed between the two frame members 11 and 12 and includes a drum member 57, which is of octagonal configuration in transverse section and is formed at the opposite ends thereof with trunnions 58 and 59, which rotatably engage through the bearing supporting members 29. The bearing supporting member 29 is provided with an opening 60 and one side of the supporting member 29 is formed with a V-shaped cutout 61 in which a V-shaped bearing cap 62 is adapted to engage. The cap 62 is held in operative position by means of a pair of bolts 63, which engage through the upper and lower portions of the cap 62 and through the bearing supporting member 29 as shown in Figure 5.

The trunnion 59 is formed with a reduced shaft extension 64 which may be square in transverse section and a hand wheel 65 is mounted on the extension 64 so that rotation of the wheel 65 will rotate the drum member 57, so as to wind the cloth thereabout. The inner side of the wheel 65 has secured thereto a ratchet or toothed annular member 66 and a pawl 67 mounted on a pivot 68, carried by the upper connecting bar 24, engages the ratchet 66, so as to hold the wheel 65 and the drum 57 against rotation in one direction. The hand wheel 65 includes a plurality of radially arranged handles 69, which are in-

clined outwardly with respect to the side member 11, as shown in Figure 1.

A warp drum generally designated as 70 is rotatably carried by the rear portion of the frame structure 10 and includes a drum member 71, which is octagonal in transverse section and is provided at the opposite ends thereof with trunnions 72 and 73. The rear uprights 11 are each provided with a rearwardly extending bearing block 74, which is fixed to the rear edge of the upright 11 at a point upwardly from the lower end thereof and the trunnions 72 and 73 engage through the bearing blocks 74. The trunnion 73 is formed with a square shaft extension 75 on which a hand wheel 76 is fixedly mounted. The hand wheel 76 includes a plurality of radially arranged and outwardly inclined handles 77, as shown in Figure 2. The drum member 71 is adapted to have the warp yarn wound thereabout and this yarn is then extended forwardly over the breast roll 54 and wound about the drum 57. A ratchet 78 is fixed to one end of the drum member 71 and a pawl 79 carried by an elongated lever or pawl operator 80 is adapted to engage the ratchet 78, so as to hold the drum member 71 against rotation in one direction. The rear end portion of the lever 80 is pivotally mounted on a pivot member 81 carried by one of the bearing blocks 74 at a point above the ratchet 78 so that the lever or operator 80 will gravitally hold the pawl 79 in engagement with a selected tooth of the ratchet 78. The lever 80 extends forwardly and downwardly to a convenient position where it may be operated by a person sitting at the forward end of the frame structure 10. A horizontally disposed connecting bar 82 is fixed at the opposite ends thereof to the upper horizontal connecting bars 24 and extends therebetween above the cloth drum 56.

A plurality of heddle harnesses or frames generally designated as 83 are movably suspended within the frame structure 10. The harnesses 83 are of conventional construction and are each provided with yarn guiding eyes 84 through which the yarn 85 is adapted to loosely pass. A rockable upper lever or lam 86 is provided for each heddle frame 83 and the lams or levers 86 are pivotally mounted on a pivot member 87 engaging through a pair of upper transversely extending supporting bars 88 and 89. The bars 88 and 89 are secured to the upper horizontal frame members 18 forwardly of the connecting bar 46 and the pivot pin 87 is provided with a head or enlarged end portion 90 forming a handle so that the pin 87 may be readily withdrawn from the supporting bars 88 and 89. A key or cotter 91 is adapted to engage through the end of the pin 87 opposite from the handle 90, so as to hold the pin 87 against endwise movement. The pin or pivot member 87 engages through the lam or lever 86 at a point intermediate the ends of the lam or lever 86 and at one side of the transverse center. An eye 92 is carried by the short end 93 of the lam 86 and a harness suspending cord or flexible suspension element 94 engages through the eye 92 and is connected to a heddle frame structure 83.

A lower balancing lam or lever 95 is pivotally mounted on a pivot member 96 in the form of a shaft which extends through the upright bracing member 21 and is countersunk or embedded in one of the upright bearing supporting members 29. The free end of the lower balancing lam 95 has an eye 97 secured thereto and a flexible connecting member 98 is connected at

one end to the eye 97 and at the other or upper end to an eye 99, which is carried by the long side 100 of the upper lam or lever 86.

There is a rockable pedal or foot lever 101 for each balancing lam 95 and the several pedals 101 are rockably mounted on a shaft 102 which is carried by a pair of depending bearing members 103, which are fixed to the rear connecting bar 41. A plurality of spacer members 104 may be mounted on the shaft 102 outwardly from the pedals or levers 101, so that if desired an additional number of pedals may be mounted on the shaft 102 where additional harnesses are to be provided for the loom. The shaft 102 is held against endwise movement by means of a pair of pins or keys 105 which engage against the outer sides of the bearings 103. Each pedal or harness operator 101 is connected to a lower balancing lam or lever 95 by means of a flexible connecting member 106 which at its lower end engages in an eye 107 carried by a pedal 101 and at its upper end engages in an eye 108 carried by the lower side of a lower lam or balancing lever 95.

There is also provided for each harness 83 a counterbalancing lam or lever 109, which is rockably mounted on a shaft 110 engaging through the upright members 21 and 29. The lam 109 is connected with a corresponding heddle frame or harness 83 by means of a flexible connecting member 111 which at its lower end engages in an eye 112 carried by the upper side of the counterbalancing lam or lever 109 and at its upper end engages an eye 113 carried by the lower end portion of a heddle frame structure 83. The counterbalancing lams 109 are of such weight as to gravitatively and normally maintain a heddle frame structure 83 in a lowermost position. Downward rocking of a pedal 101 will raise a selected heddle frame 83 and in normal operation the selected one or more of the pedals 101 are held in a lowermost position to thereby raise the selected heddle frames in order to provide the desired shed between selected warp yarns 85.

A weft beater structure generally designated as 114 is swingably carried by the frame structure 18 and includes a pair of horizontally disposed frame members 115 and 116 which are connected together by vertically disposed side frame members or bars 117. The side frame members 117 extend upwardly above the two parallel beater frame members 115 and 116, as shown in Figures 3 and 4 of the drawings. A reed structure 118 is disposed between the two lower beater frame members 115 and 116 and may be of any desired construction depending generally upon the character of the yarn forming the warp and weft. The side frame members or suspension bars 117 extend upwardly and are loosely disposed in openings 119, which are formed adjacent the opposite ends of a horizontally disposed connecting bar 120, which connects the upper end portions of the bars 117 together. The upper ends of the suspension bars 117 are provided with a plurality of vertically spaced apart openings or sockets 121 in a selected one of which a cylindrical bolt or lock 122 is adapted to engage, so as to thereby position the reed structure 118 in the desired relation with respect to the warp yarns 85. The bolt or locking member 122 is slidable in guides 123 fixed to the upper side of the connecting bar 120 and a handle or knob 124 is carried by the bolt 122

or locking member 122 to facilitate movement of the bolt in a selected socket or recess 121.

Each upper horizontal frame member 18 has mounted on the upper side thereof a vertically disposed plate 125 formed with a plurality of notches 126. The plate 125 is formed with a pair of right angularly disposed ears 127, which are adapted to be secured by fastening devices 128 to the upper side of the upper frame member 118. The upper connecting bar 120 has fixed adjacent the opposite ends thereof and inwardly from the suspension bars 117 a pair of downwardly extending plates or pivot members 129 which are adapted to engage in selected notches 126 of the plate 125. The plate or pivot member 129 has secured to the upper end thereof a base plate 130, which is fixed by fastening devices 131 to the under side of the connecting bar 120. In this manner the beater member 114 may be swingably suspended from the upper frame members 18 in the desired position with respect to the breast roll 54 and the heddle frame members 83. Each pivot member or plate 129 is formed with a downwardly extending tongue or lug 132, which is adapted to engage against the inner side of the plate 125 so that the upper frame bar 120 will be held against endwise movement by the two tongues or lugs 132 carried by the two plates or pivot members 129.

In the use and operation of this loom structure the warp yarn is adapted to be initially wound about the warp drum 71 and then extended forwardly from this drum through the eyes 84 of the heddle frames 83 and from the heddle frames 83 extended about the breast roll 54 and initially started on the cloth drum member 57. The desired pedals or frame operators 101 are depressed so as to thereby raise selected ones of the heddle frames 83 in order to form the conventional shed through which the shuttle is adapted to pass. The beater structure 114 is adapted to be suspended from the upper frame members 18 in the most convenient or desired position with respect to the yarn strands which are positioned between the heddle frames 83 and the breast roll 54.

By providing the drum members 57 and 71 with an octagonal outer surface these drum members will hold the warp yarn under better tension than drum members of circular configuration in transverse section or a different outer surface. As the weaving progresses the cloth drum member 57 is rotated in a clockwise direction as viewed in Figure 3, and at the same time this drum member 57 is rotated in a clockwise direction to wind the cloth thereabout, the releasing lever 80 is raised so as to move the pawl 79 to a released position with respect to the ratchet 71. The releasing lever 80 may be given a vertical rocking movement with the rotation of the cloth winding drum 57 so that the unwinding of the warp drum 71 will be accomplished in a step-by-step movement. Release of the pawl operating lever 80 will gravitatively effect engagement of the pawl 79 with a selected tooth of the ratchet 79 so as to hold the warp drum 71 against unwinding. The desired tension may be applied to the warp yarn by rotation of the cloth drum 57 without rotation of the warp drum 71.

What I claim is:

In a hand loom, a frame, a plurality of heddle harnesses in said frame, a suspension lever for each harness, means pivotally mounting said

levers in the upper portion of said frame, means supporting said harness from said suspension lever, a second or balancing lever for each harness, means pivotally supporting said second levers in the lower portion of the frame, means connecting the free end of each of said second levers to each of said first levers respectively, a third or counterbalancing lever for each harness, means pivotally mounting an end of each third lever in said frame between said second levers and said harnesses, means connecting the free end of each of said third levers with the

lower portions of each harness respectively, a combined harness operating pedal and balancing lever for each harness, means pivotally mounting said pedals in said frame below said second levers, and means connecting each of said pedals to each of said second levers respectively, downward pressure on selected ones of said pedals effecting elevation of selected ones of said harnesses, the remaining of said harnesses being 10 gravitantly held in a lowered position by weight of said third levers.

JOHN P. BEXELL.
